United States Patent Office.

A. V. HEYDEN, OF MILWAUKEE, WISCONSIN.

Letters Patent No. 62,832, dated February 26, 1867.

IMPROVEMENT IN BAG-HOLDERS.

The Schedule referred to in these Letters Patent and making part of the same.

TO ALL WHOM IT MAY CONCERN:

Be it known that I, A. V. HEYDEN, of the city and county of Milwaukee, and State of Wisconsin, have invented a new and useful Improvement in Bag-Holders; and I do hereby declare that the following is a full, clear, and exact description thereof, which will enable those skilled in the art to make and use the same, reference being had to the accompanying drawings, forming part of this specification, in which—

Figure 1 is a perspective view; and

Figure 2, a sectional view.

Similar letters of reference, in each of the figures, indicate corresponding parts.

The object of my invention is to enable a person to fill bags with grain or other material with facility, and without other help to hold the bags open.

A is the foundation frame; B, upright stationary standard; C, movable standard; D, platform on lever connected with standard C, having its fulcrum near its centre; E, arm connected by bolts to standards B and C; F, expanding jaws; G, fulcrum-bolts to jaws F; H, ring to hold jaws in position when expanded; I, stationary platform.

Operation.

The mouth of the bag is put over the expanding jaws, ring H being slipped down to the fulcrum G to let the jaws come together sufficient for any sized bag; then slip the ring up the handles of the jaws F, which will bring the handles together, expanding the jaws so as to hold the bag firmly open, the bottom of same resting on platform D; then fill the bag, and as the weight of material bears on the platform it settles down, throwing up the end of the lever connected with standard C, which, rising, lifts the outer end of lever E, raising the bag to its full height, enabling the operator to fill the bag full.

What I claim as my invention, and desire to secure by Letters Patent, is—

A bag-holder, when made with platform D connected to standard C, in combination with arm E, expanding jaws F, and ring H, substantially as and for the purpose described.

A. V. HEYDEN.
